UNITED STATES PATENT OFFICE:

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

PIN-SETTING MACHINE.

Application filed July 10, 1925. Serial No. 42,694.

To all whom it may concern:

Be it known that I, JOSEPH W. BISHOP, a citizen of the United States, residing at Muskegon, in the county of Muskegon and State of Michigan, have invented certain new and useful Improvements in Pin-Setting Machines, of which the following is a specification.

This invention relates to a novel and improved pin setting machine particularly of the hand operated type and has for its principal object to provide an improved device for discharging the bowling pins from the setter frame of such a machine.

15 In my co-pending application Serial No. 16,332, filed March 18, 1925, I have disclosed and claimed a setter frame comprising three horizontal decks. The top and bottom deck are joined together to operate in unison, whereas the intermediate deck is movable in respect to the top and bottom decks. A plurality of buckets is provided in the frame from which buckets the pins are released by the relative movement between the decks.

25 It is a specific object of my invention to provide improved means for causing the aforesaid relative movement and which shall operate independently of the alley bed, so that contact of any part of the setter frame with the alley-bed is not necessary for the operation of the device.

A further object of my invention is to provide novel and improved means for retarding the upward movement of the setter frame to prevent injury thereto.

35 A still further object of my invention is to provide a catch to hold together the decks of the setter frame in such a position as to hold the pins therein, whereby the frame may be raised with the pins in vertical position therein. This arrangement is of particular value where it is desired to pick up the pins left standing on the alley bed after a spare, so that the "dead wood" may be removed, when the frame may be again lowered to replace the pins which were picked up.

40 In the accompanying drawings in which I have shown a selected embodiment of my invention.

Fig. 1 is a longitudinal section through an alley bed showing my improved pin setting machine in place upon the bed.

45 Fig. 2 is a section on the line 2—2 of Fig. 1, but drawn to an enlarged scale.

Fig. 3 is a view similar to Fig. 1 showing a portion of the mechanism therein in a different position.

Fig. 4 is a view similar to Fig. 3, but showing the mechanism in still another position.

50 Figs. 5, 6 and 7 are diagrammatic views of portions of the mechanism shown in Figs. 1, 2, 3 and 4 in the various positions which they take.

55 Figs. 8, 9 and 10 are views similar to Figs. 5, 6 and 7, but showing a modification of my invention.

60 Fig. 11 is a perspective view of the catch for securing the decks of the setter frame together.

65 Referring now to the drawings I have shown at 1 an alley bed of any usual construction having mounted at the sides thereof a suitable support exemplified by the 70 posts 2, one of which is placed on either side of the bed and which support cross bars 3 on which are mounted a plurality of brackets 4.

75 The setter frame designated generally at 80 5 comprises three horizontally disposed decks 6, 7 and 8. The top and bottom decks 6 and 8 are joined together to operate as one in the manner set forth in my aforesaid co-pending application Serial No. 16,332. Vertical movement of the setter frame is insured by means of one or more guide rods 9, which are provided with heads 10 and which slide within guide tubes 11, within which tubes the heads fit snugly. The upper ends 85 of the guide tubes are preferably closed, as shown at 12 and the tubes provided with vents 13 and 13'. The vent 13 is placed at the end of each tube while the vent 13' is disposed on the side of the tube.

90 By this arrangement, the upward movement of the setter, under the influence of a counterbalance or other lifting means of any kind, is comparatively rapid until the heads 10 pass the vents 13', these vents being relatively large 95 and of sufficient size to permit ready escape of air therethrough. After the heads 10 pass these vents 13' the upward movement will be checked due to the compressed air at the top of each tube which air escapes 100 slowly through the relatively small vents 13. The above described structure exemplifies pneumatic means for retarding the upward movement of the frame and acts in such a way as to prevent damage to the va- 110

rious parts of the mechanism. Upward movement of the setter frame may be caused in any desired manner, but I have indicated it in this application as being caused by means of connecting links 14 pivoted to the intermediate deck 7 and also to levers 15, which levers are acted upon by springs contained in the cylinders 16. For further disclosure of this construction reference is made to my co-pending application Serial No. 40,727, filed July 1, 1925.

The setter frame may be lowered by means of a handle 17 having arms 18 pivoted to ears 19 upon the support and which arms are pivoted by links 20 to the intermediate deck 7 of the frame. In practice I use two arms 18 connected by the handle 17 and two links 20, but this number may obviously be modified as desired. By means of the handle 17 the frame may be lowered from the position shown in Fig. 1 to that shown in Fig. 4, and it will be obvious that the arrangement of the arms and links provides a toggle, which is straightened out when the frame is in its lowermost position, so as to make it easy to hold the frame in this position.

Referring now particularly to Figs. 5, 6 and 7, where parts not essential to an understanding of the operation of the invention are removed, it will be seen that each link 20 is provided with a rearwardly extending arm 21 having a pin 22 received within an elongated slot 23 in a link 24 pivoted to the lower deck 8. In Fig. 5 the parts are shown in the position which they occupy when the setter frame is raised. As the handle 17 is depressed, however, the intermediate deck 7 is lowered and of course carries with it the top and bottom decks, the top deck being supported upon the intermediate deck, as set forth in my aforesaid co-pending application Serial No. 16,332. During this lowering movement the pin 22 moves to the other end of the slot 23, to the position shown in Figs. 3 and 6, this position being reached when the frame is nearly in position to discharge the pins on the alley bed. Continued depression of the handle 17 will cause the pin 22 to exert a lifting force upon the link 24 and consequently upon the decks 6 and 8, in respect to the intermediate deck 7 and the parts will assume the position shown in Fig. 7, when the setter frame has reached its lowermost position. This position is shown in Fig. 4 as well as Fig. 7. Upon release of the handle 17 the springs in the cylinder 16, or any other counterbalancing means which may be employed for the purpose, will cause the frame to rise and the parts will then resume the position shown in Figs. 1 and 5. It will be noted that the arrangement of the pin 22 in the slot 23 provides a lost motion connection between the handle 17 and the

top and bottom decks of the frame, whereas a positive connection between the handle and the intermediate deck 7 is had at all times, thereby making possible the lowering of the decks in unison to a certain desired point at which point the lost motion is taken up and relative movement between the decks is obtained.

Referring now to Figs. 8, 9 and 10, I have shown a preferred form of a lost motion connection, which is somewhat simpler than that shown in Figs. 5, 6 and 7 and which also provides means for adjustment of the relative movement of the decks when such adjustment is necessary. The initial raised position of the parts is shown in Fig. 8 and it will be seen that I have replaced the link 24 with a link 25 pivoted to the arm 21 on a stationary pivot 26, instead of with a loose pivot as shown in Figs. 5, 6 and 7. This link is preferably in the form of a rod, which extends through one of the connecting plates 27 on the bottom deck 8 and is threaded to receive a nut 28 and a jam nut 29, by means of which a proper adjustment may be made of the relative movement between the decks. The operation of this modification is the same as that shown in Figs. 5, 6 and 7. The intermediate position corresponding to that of Fig. 6 is shown in Fig. 9 wherein it will be seen that the lost motion has been taken up by the nut 28 being brought into engagement with the bottom of the plate 27. Then further depression of the handle 17 will cause the relative movement between the decks until they reach the position shown in Fig. 10.

As described in my aforesaid co-pending application, Serial No. 16,332 the intermediate deck 7 is provided with a plurality of shoes 30 by means of which the pins are grasped as they are about to be placed upon the bed and are properly centered thereon. These shoes are normally released upon raising of the setter frame so as to leave the pins standing upon the bed. However, when a spare has been made, that is when certain pins have been knocked down and others remain standing and it is desired to remove the "dead wood," which is a term applied to the pins which have been knocked down, it is desirable to lift the standing pins from the alley bed and to replace them thereon. For that purpose I provide means for securing the decks in the position shown in Figs. 4, 7 and 10 in which position the shoes 30 are held in engagement with the pins, as set forth in my aforesaid co-pending application, Serial No. 16,332. This means is exemplified by a catch comprising a single rod 31 disposed upon one of the connecting plates 27 on the bottom deck and mounted in ears 32 on said plate. The two ends of the rod are bent upward, as shown and provided with detents 33 and 34 to engage the

angle bar 35, forming a part of the intermediate deck 7. In order to move the detents 33 and 34 into engagement with the bar 35, one end of the rod is continued upwardly as at 36 to form a handle whereby the detents may be brought into the position, shown in Figs. 7 and 10. When brought into this position and downward pressure upon the handle 17 is removed, the tendency of the decks 7 and 8 to separate will retain the detents in engagement with the bar 35. Pressing down upon the handle 17 will permit the detents to be released and to insure this release I provide a coil spring 37 tending to rotate the rod 31 in a direction to move the detents to the position shown in Figs. 5, 6, 8 and 9. When the decks are secured together, as shown in Figs. 7 and 10, the entire frame 20 may be lifted by the handle 17 together with any pins which may have been left standing upon the alley bed. When the catch is in position to hold the decks together I find that the frame will remain in its lowermost 25 position until lifted by the handle. This is due to the fact that the spring or other counterbalancing device must, in its initial operation, lift not only the intermediate deck 7 against the action of the toggle 30 formed by the arms and links, but must also lift the top and bottom decks. However, a very slight lifting movement on the handle is all that is necessary to start the frame in its upward movement.

35 From the above it will be apparent that I have provided a pin setting machine having a very simple and effective means for causing relative movement between the decks of the setter frame to discharge the pins together with a catch which increases the field of usefulness of the machine by permitting it to be used for lifting and replacing pins remaining on the alley bed after a spare. Moreover, the provision of 40 the vents in the tops of the guide tubes provides a dash-pot arrangement which will permit rapid upward movement of the setter frame, but will brake or retard the same to prevent injury to the parts by too abrupt 45 movements and stops.

50 I am aware that changes in the form, construction and arrangement of parts may be made without departing from the spirit and without sacrificing the advantages of the invention and I reserve the right to make all such changes as fairly fall within the scope of the following claims:

I claim:

1. In a pin setting machine, a setter frame 55 comprising a pair of horizontally disposed decks, means for lowering said decks, and means for causing relative vertical movement between said decks and comprising a lost motion connection.

65 2. In a pin setting machine, a setter frame

comprising a pair of horizontally disposed decks, a handle having a positive connection with one of said decks and having a lost motion connection to the other of said decks to cause relative movement therebetween. 70

3. In a pin setting machine, a setter frame having a top and bottom deck moving in unison, an intermediate deck disposed between said top and bottom deck and supporting said top deck, a handle having a 75 positive connection to said intermediate deck to lower the same and having a lost motion connection to said top and bottom decks, for the purpose set forth.

4. In a pin setting machine, a setter 80 frame comprising top and bottom decks secured together, an intermediate deck disposed between said top and bottom decks, a handle having connections to said top and bottom decks and to said intermediate deck, 85 said connections causing said decks to move in unison upon depression of said handle and to move relatively to each other upon further depression of said handle.

5. In a pin setting machine, a setter frame 90 comprising a top and bottom deck secured together, an intermediate deck disposed between said top and bottom decks, a handle and connections between said handle and said decks causing said decks to be lowered 95 in unison upon depression of said handle to a certain extent and causing said top and bottom decks to be lifted in respect to said intermediate deck upon further depression of said handle. 100

6. In a pin setting machine, a setter frame comprising top and bottom decks secured together, an intermediate deck disposed between said top and bottom decks, a handle connected to said intermediate deck by a 105 link, an arm on said link, and a connection between said arm and said top and bottom decks permitting said decks to be lifted in unison to a certain point and then causing said top and bottom decks to be raised in relation to said intermediate deck. 110

7. In a pin setting machine, a setter frame comprising top and bottom decks secured together, an intermediate deck disposed between said top and bottom decks, a handle 115 connected to said intermediate deck by a link, an arm on said link, and a lost motion connection between said arm and said top and bottom decks, for the purpose set forth.

8. In a pin setting machine, a setter frame comprising top and bottom decks secured together, an intermediate deck disposed between said top and bottom decks, a handle connected to said intermediate deck by a link, an arm on said link, and a lost motion 125 connection between said arm and said top and bottom decks, said lost motion connection comprising a plate on said bottom deck, a rod pivoted to said arm and passing through said plate, and a nut threaded on 130

the end of said rod, for the purpose set forth.

9. In a pin setting machine, a setter frame comprising top and bottom decks secured together, an intermediate deck disposed between said top and bottom decks, a handle connected to said intermediate deck by a link, an arm on said link, and a lost motion connection between said arm and said top and bottom decks, and means for adjusting said lost motion connection to vary the amount of relative movement between said decks, for the purpose set forth.

10. In a pin setting machine, a setter frame, means for raising and lowering said frame, means for guiding said frame in a vertical direction, and pneumatic means for retarding the upward movement of said frame.

11. In a pin setting machine, a setter frame, means for raising and lowering said frame, means for guiding said frame to move in a vertical direction and comprising a guide tube, a guide rod slidable in said tube and having a head thereon, the top of said guide tube being closed and having a vent therein.

12. In a pin setting machine, a setter frame comprising top and bottom decks, an intermediate deck disposed between said top and bottom decks, means for causing relative movement between said decks to place the pins carried by said frame and a catch to hold said decks in position to place said pins.

13. In a pin setting machine, a setter frame comprising a pair of horizontally disposed decks, a handle having a positive con-

nnection with one of said decks and having a lost motion connection to the other of said decks to cause relative movement therebetween, and means for adjusting said lost motion connection.

14. In a pin setting machine, a setter frame comprising top and bottom decks secured together, an intermediate deck disposed between said top and bottom decks, a handle connected to said intermediate deck by a link, an arm on said link, a lost motion connection between said arm and said top and bottom decks, and means for adjusting said lost motion connection.

15. In a pin setting machine, a setter frame, means for raising and lowering said frame, means permitting free upward movement of said frame to a certain point, and means for retarding said upward movement beyond said point.

16. In a pin setting machine, a setter frame, means for raising and lowering said frame, means for guiding said frame to move in a vertical direction and comprising a guide tube, a guide rod slidable in said tube and having a head thereon snugly fitting within said tube, said tube having a vent in one side thereof, said vent being of a size to permit free escape of air therethrough, said tube having a second vent adjacent the end thereof, said second vent being of a size to permit gradual escape of air therethrough whereby upward movement of said head will be checked after it has passed said first named vent.

JOSEPH W. BISHOP.
